H. B. Mitchell.

Lacy & Lacy, Attorneys

UNITED STATES PATENT OFFICE.

HOWARD B. MITCHELL, OF TACOMA, WASHINGTON.

ASSEMBLING TOOL FOR INTERRUPTER ARMS.

Application filed September 17, 1921. Serial No. 501,491.

To all whom it may concern:

Be it known that I, HOWARD B. MITCHELL, citizen of the United States, residing at Tacoma, in the county of Pierce and State of Washington, have invented certain new and useful Improvements in Assembling Tools for Interrupter Arms, of which the following is a specification.

This invention relates to an improved tool 10 for removing or replacing the interrupter arm of the distributor of an engine ignition system and seeks, among other objects, to provide a very simple and efficient tool whereby the operation of removing and replacing 15 an interrupter arm with its spring may be easily and quickly accomplished.

A further object of the invention is to provide a tool constructed to retain the interrupter arm thereon so that the interrupter arm may be readily manipulated by means of the tool in the restricted space of a distributor casing.

And the invention has as a still further object to provide a tool adapted to retain the 25 interrupter arm spring assembled upon the hub of the arm and wherein the spring will be held under tension by the tool so that the arm and spring may be readily arranged in operative position within the distributor.

30 Other and incidental objects will appear hereinafter.

In the drawing:

Figure 1 is a plan view showing a distributor of conventional design, the cover being 35 removed,

Figure 2 is a perspective view showing the interrupter arm and spring of the distributor assembled upon the tool of the present invention,

40 Figure 3 is a perspective view showing the tool in detail,

Figure 4 is a longitudinal sectional view taken medially through the tool,

45 Figure 5 is a longitudinal sectional view showing a slight modification of the invention, and

Figure 6 is a detail perspective view of the modified structure.

This invention is particularly designed 50 for use in connection with a distributor known as the Remy distributor and in order to clearly bring out the construction and manner of use of the device I have, in the drawing, shown the tool in conjunction with 55 a Remy distributor. In Figure 1 such a distributor is illustrated, the usual cap being

removed. Briefly stated, the distributor comprises a casing 10 and extending through the casing is a shaft 11 upon which is mounted a cam 12. Extending within the casing is 60 a post 13 carrying an adjustable contact 14 and mounted to rock within the casing is an interrupter arm 15 provided at its free end with a contact point 16 to cooperate with the contact 14. This arm further carries a block 65 17 of insulating material which is engageable by the cam 12 for rocking the arm and breaking the circuit between the contacts 14 and 16 and formed on the arm at its inner end is a hub 18 from which projects a spindle 19. The spindle is removably received in a suitable socket within the casing and arranged in the rear of said socket is an 70 150 standing post 20 carrying a spring clip 21 normally bearing over the inner end of the 75 arm for holding said arm against accidental displacement. Surrounding the hub 18 of the arm is a spring 22 one end of which is formed with a hook 23 engaging over the forward edge of the arm near its inner end 80 while the opposite end 24 of said spring extends rearwardly to coact with the post 20 so that the spring is normally held under tension urging the arm 15 to closed position. In practical use, it is often found necessary 85 to polish the contact 16 of the arm and to accomplish this it is, of course, necessary to remove the arm. A like situation arises where the spring 22 becomes impaired. How- 90 ever, as will be at once appreciated, consider- 95 able difficulty is experienced in manually removing and replacing the arm with its spring 22, due to the restricted space within the distributor casing. The present invention, therefore, seeks to provide a tool where- 95 by the operation of removing or replacing the arm with its spring may be easily and quickly accomplished.

In carrying the invention into effect, I employ a stock or barrel 25 which is prefer- 100 ably formed of metal and tightly fitting in the barrel is a core 26. This core is prefer- ably of suitable insulating material and ex- tends from the inner end of the barrel to a point near the outer end thereof, the inner 105 terminal of the core being counterbored, as indicated at 27, to accommodate the head upon the upper end of the spindle 19 of the interrupter arm 15. Extending transversely through the outer end of the barrel and 110 through the core is a cross pin 28 locking the core within the barrel and providing a han-

dle for the tool. Formed in the inner end of the barrel at one side thereof is a longitudinally extending slot 29 while at its adjacent end edge the barrel is further provided with 5 a notch 30 arranged opposite said slot. The forward end wall of said notch is undercut, as indicated at 31, while between said end wall of the notch and the forward side wall of the slot 29, the barrel is cut away to provide 10 an inclined end edge or face 32. As will be perceived, the tool is exceedingly simple in its construction and may be readily produced.

To remove the arm 15 with its spring 22, 15 the working end of the barrel 25 is fitted over the inner end of the arm, the arm being accommodated in the slot 29. The barrel is then rotated in a clockwise direction until the notch 30 is brought opposite the end 24 20 of the spring when, by pushing inwardly upon the barrel said end of the spring is engaged in said notch. This done, the tool may be lifted upwardly for removing the arm and spring. Thus, as will be seen, the 25 arm may be readily displaced for polishing the contact point 16 of the arm. To replace the arm, the operation just described is reversed. First, the arm is fitted in the working end of the barrel in the manner suggested in Figure 2, the arm projecting through the slot 29. The spring 22 is then assembled 30 upon the hub 18 of the arm and the hook 23 of the spring engaged with the forward edge of the arm. The end 24 of the spring is 35 then grasped and swung in a clockwise direction against the inclined edge 32 of the barrel until said end of the spring drops into the notch 30. The undercut end wall of this notch will then securely hold the end 24 40 of the spring against accidental displacement from the notch so that the tool may be grasped for directing the spindle 19 of the arm into the spindle socket of the distributor. During this operation, the clip 21 is, of 45 course, swung to one side so that the end 24 of the spring may shift to a position behind the post 20. Thus, by then rocking the barrel slightly, the barrel may be disengaged from the spring and removed, leaving the 50 interrupter arm and spring in operative position upon the distributor. Accordingly, the interrupter arm with its spring may be replaced with facility.

In Figures 5 and 6 of the drawing, I have 55 illustrated a slight modification of the invention wherein a barrel 33 is employed, this barrel corresponding to the barrel 25 of the preferred construction and being provided at one side with a slot 34 corresponding to 60 the slot 29. Fixed in the outer end of the

barrel is a short core 35 preferably of insulating material and extending through the barrel and said core is a cross pin 36 providing a handle. Opposite the slot 34, the barrel is provided in its adjacent end edge 65 with an inclined notch 37 defining an overhanging hook 38 for engagement with the end 24 of the interrupter arm spring, the notch 37 corresponding to the notch 30 of the preferred construction. From the forward 70 side wall of the slot 34, the barrel is formed with an inclined end edge 39 sloping upwardly to the hook so that the inner end of the spring may be easily caused to ride over said edge to engage in the notch. It will accordingly be seen that this modified form of the invention also provides a very effective tool.

Having thus described the invention, what is claimed as new is:

1. A tool of the character described including a stock formed to accommodate an interrupter arm and provided with means for holding said arm against swinging movement and with additional means to engage a spring upon the arm tensioned to swing the arm. 80 85

2. A tool of the character described including a stock formed to accommodate an interrupter arm and provided with means for holding said arm against swinging movement and with a notch to accommodate one end of a spring upon the arm tensioned to swing the arm. 90 95

3. A tool of the character described including a stock formed to accommodate an interrupter arm and provided with a slot to receive the arm for holding the arm against swinging movement, and means upon the stock to engage a spring upon the arm tensioned for swinging the arm. 100 105

4. A tool of the character described including a stock formed at one end to receive the inner end of an interrupter arm and provided with a slot to accommodate the arm holding the arm against swinging movement, and means upon the stock to engage a spring tensioned to swing the arm, the stock being formed with an inclined face sloping away from said means. 110

5. A tool of the character described including a stock formed to receive the inner end of an interrupter arm therein and provided with a slot to accommodate said arm holding the arm against swinging movement, there being a notch formed in the stock for holding one end of a spring tensioned to swing the arm. 115

In testimony whereof I affix my signature.
HOWARD B. MITCHELL. [L. S.]
